BY
Finchel & Finchel,
ATTORNEY-S

UNITED STATES PATENT OFFICE.

JESSE C. HOWARD, OF COLUMBUS, OHIO.

HYDRAULIC AIR-COMPRESSOR.

SPECIFICATION forming part of Letters Patent No. 643,962, dated February 20, 1900.

Application filed October 24, 1899. Serial No. 734,648. (No model.)

To all whom it may concern:

Be it known that I, JESSE C. HOWARD, a citizen of the United States, residing at Columbus, in the county of Franklin and State 5 of Ohio, have invented certain new and useful Improvements in Hydraulic Air-Compressors; and I do hereby declare the following to be a full, clear, and exact description of the invention, such as will enable others skilled 10 in the art to which it appertains to make and use the same.

The object of my invention is to provide an improved construction in which leakages, rapid wear or destruction of packings, dead- 15 centers, noise, and other objections common to apparatus of this kind now upon the market are overcome.

The accompanying drawing, showing one embodiment of my invention, presents a central vertical sectional view taken on a plane through the supply-inlet and the outlet openings, except as to the cut-off tube, which is shown partially in elevation and partially in section, and the air-compressor cylinder and 25 its contained parts are broken out at two places.

1 designates the base; 2, the casing containing the hydraulically-operated pistons and valves; 3, the air-compressor cylinder; 30 4, a cap for the air-compressor cylinder, in and upon which are the usual or any approved devices for admitting air to the air-compressor and checking it after it is compressed.

The casing 2 has water-inlet 5 and water- 35 outlet 6, ports with valve-seats 7 and 8, a passage 9, connecting inlet 5 through the supply-port at valve-seat 8 with the chamber of air-compressor cylinder 3. The casing 2 also has just below the inlet-port 5 a cylindrical 40 piston-chamber 10 and below this a larger cylindrical piston-chamber 10^a, the latter connected with outlet 6 by a passage 11. The chamber of cylinder 3 communicates with outlet 6 through an exhaust-port having valve-seat 7. The sides of the chambers 10 and 10^a 45 are smooth and unbroken by ports or orifices where the pistons hereinafter described play.

The main-valve stem I prefer to make of two parts 12 and 12^a, threaded together, so as 50 to permit adjustment of the valves thereon with respect to each other. This valve-stem has an axial opening, as indicated at 12^b, en-

larged in its lower portion, as indicated at 12^c. The valve-stem has two valves 13 and 13^a, that fit the seats 7 and 8 of the exhaust 55 and supply ports, respectively; but these valves are located at such distance apart that one of the ports may be closed while the other is open. The valve-stem reciprocates in an opening in a web between the seats 7 and 8, 60 and to make this place water-tight I provide a cup-leather or packing 19, held by a nut 19^a. The outer side of the lower end of the portion 22^a of the valve-stem is furnished with a piston composed of cup-leather or packing 14, 65 supported on and by a flanged ring 14^a. This piston fits and works in the chamber 10. Below 10^a is another piston of larger diameter composed of a cup-leather or packing 15, held be- 70 tween a ring 15^a and a flanged nut 15^b, thread- 15 onto the lower end of the portion 12^a. In the enlarged portion 12^c of the axial opening in the valve-stem are two small cylinders 16 and 17 with cup-leathers or packings 16^a, 17^a, 75 17^b, arranged at the ends of and between the two cylinders, as shown, all of which cylinders and cup-leathers or packings are held together and in place between washer 17^c at the upper end and a nut 18, threading into 80 the lower end of the opening 12^c. Within the axial opening of the valve-stem, and in which the cup-leathers 16^a, 17^a, and 17^b are fitted, is the cut-off tube 20. This tube is closed at its upper end and open at its lower. It is also 85 provided with an opening or openings 20^d.

The valve-stem and cylinder 16 are pro- 90 vided with openings 23 and 24, respectively, to admit water from above the cup-leather 14 into the tube 20 when the openings 20^d therein are opposite cylinder 16, and the ring 14^a and valve-stem and cylinder 17 are provided with openings 21 and 22 below that cup-leather, but above cup-leather 15, to allow water to ex- 95 hault from below that cup-leather through tube 20 and passage 11, when the openings 20^d are opposite cylinder 17.

In the position of the parts within the cas- 100 ing 2, as shown in the drawings, the water under pressure through inlet 5 has access to the lower end of the usual weighted air-compressing piston in the cylinder 3 and to the upper side of the piston in the chamber 10. This pressure forces the valve 13 down on its

seat 7, closing the port there, and lifts the air-compressing piston. Just before the air-compressing piston has risen to its limit the cut-off tube 20 is lifted by the nut 20^b in the tube 20^c of the air-compressing piston, so as to bring the openings 20^d into communication with the ports 23 and 24. This shifting of the tube 20 allows the pressure of the supply to act on the under side of the piston in the chamber 10^a, which, being of larger diameter than the piston in chamber 10, preponderates and forces the valve-stem up and the valve 13 out of its seat and closes the valve 13^a upon its seat 8. The water in the air-compressor chamber 3 then discharges through the port at seat 7, the air-compressor descending by gravity. At the proper time the upper end of the tube 20^c strikes the upper end of the rod 20^f of the tube 20, or, if preferred, a cap 20^e on the stem, shifting the openings 20^d to a position below the cup-leather 17^a and again into communication with the ports 21 and 22. This shifting of the tube 20 cuts off the pressure from the under side of the piston in the chamber 10^a and allows the pressure on the valve in chamber 10 to again close the valve 13 on its seat when the operation is repeated. When the valve-stem is forced down by pressure on the valve in chamber 10, the water below the piston in chamber 10^a exhausts through openings 20^d, 21, 22, 11, and discharge 6.

12^a is an annular cushion to take the impact of the air-compressing piston at the end of its descent.

What I claim, and desire to secure by Letters Patent, is—

1. In a hydraulic air-compressor, the casing 2 having supply and exhaust ports with valve-seats 8 and 7, respectively, and piston-chambers 10 and 10^a, a valve-stem having valves for the seats 8 and 7, pistons in the

chambers 10 and 10^a, with means for automatically changing the pressure from one piston to the other, substantially as described. 45

2. In a hydraulic air-compressor, the casing 2 having supply and exhaust ports with valve-seats 8 and 7, respectively, piston-chambers 10 and 10^a, a valve-stem having valves for the seats 8 and 7 and pistons for the chambers 10 and 10^a, a tubular cut-off valve reciprocating within said valve-stem provided with openings for admitting and cutting off the pressure-supply to the piston-chamber 10^a, substantially as shown and described. 55

3. The casing provided with supply and exhaust ports and piston-chambers 10 and 10^a, a valve-stem having valves for the supply and exhaust ports, separate pistons for the chambers 10 and 10^a, openings in said valve-stem, a cut-off tube in said stem adapted to alternately admit water to and exhaust water from the chamber 10^a, substantially as described. 60

4. In a hydraulic air-compressor, the casing 2 having supply and exhaust ports with valve-seats 8 and 7, respectively, piston-chambers 10 and 10^a, and outlet 6, a valve-stem having valves for the seats 8 and 7, pistons for chambers 10 10^a, openings 23 and 21 communicating, respectively, with chambers 10 10^a, cylinders 16 and 17 each provided with an opening to register with openings 23 and 21 fitted within the valve-stem, and a cut-off tube reciprocating within the valve and cylinders 16 and 17, substantially as shown and for the purpose described. 65 70 75

In testimony whereof I affix my signature in presence of two witnesses.

JESSE C. HOWARD.
